JOHN K. ROGERS, OF BROOKLINE, MASSACHUSETTS.

Design No. 4,530, dated December 20, 1870.

DESIGN FOR A TYPE.

The Schedule referred to in these Letters Patent and making part of the same.

I, JOHN K. ROGERS, of Brookline, county of Norfolk and State of Massachusetts, have invented and produced a new and original Design for Printing-Types, of which the following is a specification.

The nature of my design, which I call Bank-Note Italic, is fully represented in the accompanying specimen impression, to which reference is made.

I claim as my invention—
The design for printing-types, as shown.
JOHN K. ROGERS.
